FIG. 3.

INVENTOR
Solomon Cantor
BY Munn & Co.
ATTORNEYS

UNITED STATES PATENT OFFICE.

SOLOMON CANTOR, OF NEW YORK, N. Y.

BROOM.

1,390,882.

Specification of Letters Patent. Patented Sept. 13, 1921.

Application filed November 11, 1920. Serial No. 423,426.

To all whom it may concern:

Be it known that I, SOLOMON CANTOR, a citizen of the United States, and a resident of the city of New York, borough of Manhattan, in the county of New York and State of New York, have invented a new and Improved Broom, of which the following is a full, clear, and exact description.

This invention relates to improvements in brooms, and more particularly to double-ended brooms which are capable of reversal so that both ends of the broom can be used and thus result in economy to the user.

A further object is to provide a double-ended broom having an improved arrangement of corn or straw whereby the smaller ends of the corn or straw are at the outer ends of the broom and the larger or thicker ends of the corn or straw are at the intermediate portion of the broom, and this is accomplished by forming the broom of two independent clusters or sets of corn or straw having their inner larger ends clamped or otherwise fixed together so that the broom at its intermediate portion is contracted and at both ends is given the desired flare.

With these and other objects in view the invention consists in certain novel features of construction, and combinations and arrangements of parts, as will be more fully hereinafter described and pointed out in the claims.

In the accompanying drawings—

Figure 1 is a view mainly in elevation, but partly broken away, illustrating my improved broom.

Fig. 2 is an edge view of Fig. 1.

Fig. 3 is a view in longitudinal section through the intermediate portion of the broom.

My improved broom as illustrated clearly in the drawings, consists of two clusters 1 and 2 which are formed of any desired quantity of ordinary broom corn, and for purposes of description we shall hereinafter refer to the parts 1 and 2 as brushes, the two brushes together constituting a broom.

The brushes 1 and 2 while reversely positioned, are constructed precisely alike. Each brush is so made that the larger or thicker ends of the broom corn or straw are rigidly clamped and secured together by means of lines of stitching 3 or other form of securing means. These brushes are independently made and are contracted at the

larger inner ends of the corn or straw and are permitted to expand or flare at the outer ends of the brushes.

The two brushes 1 and 2 are rigidly secured together to form my improved double-ended broom by means of a clamp 4 which consists of a pair of sheet metal members 5 and 6 having overlapping ends and fitting around the inner ends of the brushes which constitute the intermediate portion of the broom, and secured in place preferably by rivets 7 which extend through the corn and form an effectual binding means to hold the parts rigidly together.

Integral outwardly projecting webs 8 are formed on the clamp 4, or rather on the members 5 and 6 thereof, and these webs have correspondingly reduced and enlarged ends to telescope one within the other as shown at 9 in Fig. 2. These webs 8 not only form reënforcing and strengthening means but guiding means for a broom support, which, however, forms no part of the present invention as I desire in this application to cover the broom broadly.

It will, therefore, be noted that I provide a broom which consists of two clusters of corn or straw forming brushes with the smaller ends of the corn or straw at the outer ends of the brushes and the larger or thicker ends of the corn rigidly clamped and secured together at their inner ends, thereby forming a double-ended broom having at both ends the thin ends of the corn or straw.

Various slight changes might be made in the general form and arrangement of the parts described without departing from the invention, and hence I do not limit myself to the precise details set forth, but consider myself at liberty to make such changes and alterations as fairly fall within the spirit and scope of the appended claims.

I claim:

1. A broom, comprising a pair of brushes, each brush having the larger ends of the straw or corn compressed and secured together and the smaller ends of the straw or corn flared apart, said brushes located with their larger straw ends together, a clamp comprising a pair of metal plates secured to the adjacent ends of both brushes, and webs on the plates, said webs at the ends of the plates having interlocking engagement.

2. A broom, comprising a pair of brushes,

each brush having the larger ends of the said clamps having laterally offset hollow straw or corn compressed and secured together and the smaller ends of the straw or corn flared apart, said brushes being located with their larger straw ends abutting, 5 a clamp comprising a pair of metal plates secured to the adjacent ends of both brushes, said clamps having laterally offset hollow beads, the beads of one clamp member fitting within the other, and rivets projected 10 through the clamp members and through the brushes.

SOLOMON CANTOR.
